SIPHON-BREAKING MEANS FOR LIQUID
METERING SYSTEMSWalter S. Brubaker, Oakland, Calif., assignor to
Granberg Meter Corporation, San Francisco,
Calif., a corporation of California

Application April 5, 1937, Serial No. 135,164

13 Claims. (Cl. 221—95)

The invention relates to a liquid metering system used primarily for measuring gasoline or oil as it is discharged from a tank, such systems being commonly used for filling tank trucks with gasoline or fuel oil from storage tanks, for filling the tanks of gasoline dispensing stations with gasoline from tank trucks, and for filling the tanks of oil-burning systems with fuel oil from tank trucks. With systems of this nature ordinarily relying on gravity flow, the suction or negative pressure exerted by the hose increases as the tank becomes empty and if unbroken the siphonic action in the meter produced by this suction would totally or partially empty the meter upon emptying of the tank, allowing air or gas to enter said meter and thereby causing inaccuracy both at the end of one liquid delivery operation and at the start of the next. To prevent this, it is customary to provide the system with a siphon breaker, the purpose of which is to admit air into a suitable portion of said system at the outlet side of the meter to break the siphonic action at the proper time. In certain metering systems, this air has heretofore been supplied from a chamber which is instrumental in venting air and gases from the system at the inlet side of the meter to protect the latter against entrance of such air and gases. The liquid in discharging from the tank flows through this chamber and when the tank is about empty, said chamber receives air from said tank through the same passage which conducts the liquid from said tank to said chamber, and it has been the air entering through this passage which has been used for the purpose of breaking the siphon. However, before the chamber can supply sufficient air to break the siphon, it is first necessary that said chamber contain all air required, and it very often does not. In this connection, it is to be borne in mind that the chamber receives this air through the same passage which supplies it with liquid. Therefore, this passage does not cleanly open and remain open when the tank is about empty but on the contrary, it is repeatedly opened and closed due to flow of "slugs" of the liquid therethrough. The result is that the chamber often contains insufficient air to break the siphon when the siphon breaker first operates and consequently said siphon breaker must operate repeatedly before the siphon is finally broken, often allowing air or gas to enter the meter in the meantime.

It is the primary object of the present invention to overcome the above objection, and in

carrying out this end, other objects are to make novel provision for automatically conducting the siphon-breaking air from two independent sources to insure an adequate supply thereof, one of said sources being preferably the aforesaid casing; to make novel provision whereby the means for conducting the siphon-breaking air also embodies means for venting air and gases from a portion of the system at the inlet side of the meter; to provide a unique relation of elements in which the movements of the ordinary vent valve for eliminating air from the aforesaid casing, act to control the passage of the siphon-breaking air from both of said sources into the system; to provide a novel relation whereby the vent valve serves to actuate an additional valve for admitting siphon-breaking air, even if the air admitted by said additional valve be the entire quantity required; and to provide a generally improved and practicable construction of simple and inexpensive nature.

With the foregoing and minor objects in view, the invention resides in the novel subject matter hereinafter described and claimed, description being accomplished by reference to the accompanying drawing.

Fig. 1 is a side elevation of a liquid metering system including the present invention.

Fig. 2 is an enlarged vertical sectional view through the combined air release device, siphon breaker, and strainer.

Fig. 3 is a detail sectional view partly in elevation as indicated by line 3—3 of Fig. 2.

Fig. 4 is a side elevation partly broken away and in section showing a different construction for the combined air release device, siphon breaker and strainer.

In the drawing above briefly described, the numeral 5 denotes a tank from which liquid is to be discharged through a meter 6 without allowing entrance of air or gas to said meter. A discharge pipe 7 has been shown extending from the bottom of the tank 5 to the inlet 8 of a combined air release device, siphon breaker and strainer 9, the outlet 10 of this combined device being appropriately connected either directly to or by piping, with the inlet 11 of the meter 6. A liquid discharge line leads from the meter and in the present disclosure includes a faucet 12 and a hose 13. The combined device 9 is connected, in the present showing, with the faucet 12, by means of an air-conducting line 14 for the purpose of admitting the siphon-breaking air at the proper time, but said device 9 could of course be connect-

ed with any part of the system forming the high point on the discharge side of the meter. While I may refer to the siphon breaker or the like 9 as being disposed at the inlet side of the meter, the language "at the inlet side" is not to be restricted as meaning directly adjacent to the meter, for the desired result could be obtained with said siphon breaker or the like 9 positioned at any suitable location between the meter 6 and the tank 5.

10 The device 9 includes a casing 15 having a chamber 16 which receives the liquid from the tank, said casing having the inlet 8 in one end and two additional inlets 8^a in its sides, in the present disclosure, so that any of said inlets may 15 be used, as most convenient, and the others closed by appropriate plates 17. The casing 15 includes a dam 18 over which the liquid must flow in leaving the chamber 16, and an appropriate bucket-type strainer 19 is provided beyond 20 this dam to strain the liquid before it reaches the outlet 10 and flows on to the meter 6. At 20, a removable plate has been shown for giving access to the strainer 19, allowing removal and cleaning of said strainer.

25 The top 21 of the casing 15 is provided with an air and gas vent 22, and an upwardly closing winged valve 23 is provided for said vent, the lower end of said valve being connected with a lever 24 which is fulcrumed at 25 in the casing 30 15 and is provided with a float 26, said float being operated by the liquid in the chamber 16.

Secured upon the casing top 21, is a valve casing 27 which communicates with the vent 22, said valve casing having an air outlet 28 which 35 is connected by the air conducting line 14 with the faucet 12 or other appropriate part of the system. Whenever flow starts, with the float 26 in lowered position and the valve 23 open, all air and gas vent from the top of the casing 15 into the valve casing 27 and flow through the line 14 beyond the meter 6 so that they cannot enter the latter. When the chamber 16 fills sufficiently 40 with liquid, this liquid raises the float 26, thereby closing the valve 23, and the gas-and-air-free liquid flows on through the meter. When the tank 5 is about empty, some air enters the chamber 16 through the line 7 and the liquid in this chamber then lowers somewhat, causing float 26 45 to move downwardly and open the valve 23. This allows passage of air from the upper end of the chamber 16 through the vent 22, valve casing 27 and air line 14 into the system at a point beyond the meter, and prior to the present invention, this air has been relied upon to break the siphonic 50 action. However, due to the fact that the line 7 does not cleanly open and remain open when the tank is about empty but on the contrary repeatedly opens and closes due to passage of "slugs" of liquid therethrough, the chamber 16 often contains an insufficient quantity of air to break the siphon the first time the mechanism operates, the result being that said mechanism must repeatedly operate before the siphonic action is 55 finally broken, often allowing air or gas to enter the meter in the meantime. I have, therefore, made novel provision for supplying air to the line 14 from a source other than the chamber 16 and entirely unaffected by flow of liquid through the 60 system, as will now be fully described.

I provide the valve casing 27 with air inlets 29 which preferably communicate with the atmospheric air at the exterior of the system, and I provide a second valve 30 for controlling said air inlets 29, said valve 30 being operatively con-

nected with the valve 23 by an extension stem 31. The portion of the valve casing 27 receiving the valve 30 is preferably in the form of a cylinder with the inlets 29 in its side wall and said valve 30 is preferably in the form of a skirted piston with slots 32 in its skirt to register with the inlets 29 when air is to be admitted.

When liquid is being discharged from the tank 5, the float 26 holds the valve 23 closed and also holds the second valve 30 in the closed position, 10 as seen in Fig. 2. When the tank 5 is about empty, however, and sufficient air enters the chamber 16 through the line 7 to allow the float 26 to drop, said float opens the valve 23 and in so doing also opens the valve 30. The result is that 15 air from a source unaffected by flow of liquid through the system, enters the inlets 29 and discharges through the outlet 28 and the air line 14, to immediately break the siphon. Simultaneously with this flow of air, some air will of course 20 flow from the upper end of the chamber 16 through the open vent 22 and on through the air line 14, but even if this air should be negligible the air supplied through the inlets 29 will be adequate to perform the siphon-breaking 25 operation. The reason why air enters at 22 and 29 and discharges as described is because the pressure at the faucet is less than atmospheric pressure due to the suction effect of the hose.

In the form of construction so far described, 30 the float-actuated valve 23 is relied upon to vent air and gases from the chamber 16 when flow starts, but instead of using a valve such as 23 and a vent such as 22 controlled by said valve, I may merely provide the top of the device 9^a 35 with a vent line 33 for this purpose, as shown in Fig. 4, said vent line leading to the top of the tank 5 or to any other suitable point. When this is done, a single stem 34 may directly connect a float-actuated lever 24^a, within the chamber 16^a, 40 with a valve 30^a within a casing 27^a, said valve 30^a and casing 27^a being preferably identical with the valve 30 and casing 27, above described. When the float 26^a drops, it opens the valve 30^a 45 and atmospheric air or air from other suitable source unaffected by the flow of liquid in the system, enters through the inlets 29^a, passes through the outlet 28^a, and flows through the air line 14^a to break the siphon.

In Figs. 1 to 3, it will be observed that air is supplied (through the inlets 29) to the line 14, in addition to the air supplied to said line through the vent 22 from the chamber 16, whereas in Fig. 4, the siphon-breaking air is supplied entirely through the inlets 29^a. In either instance, an ample supply of air is assured to cause immediate siphon-breaking upon the first operation of the mechanism and therefore it is insured that the siphonic action shall not draw air or gas into 60 the meter.

In both forms of construction, it is preferable to provide the air line 14 or 14^a with a check valve 35 which closes toward the device 9 or 9^a, for when the tank 5 is substantially full, such plus pressure exists in the delivery side of the system as to possibly cause flow of liquid through the line 14 into the casing 27.

It will be seen from the foregoing that novel and advantageous provision has been made for carrying out the object of the invention, and while the present disclosure may be considered as preferred, it is also to be considered as illustrative rather than limiting, for numerous variations may be made within the scope of the invention as claimed.

I claim:—

1. In a liquid metering system in which unbroken siphonic action would empty the meter, said system including a liquid-conducting casing through which the liquid flows to said meter; valved conducting means controlled by the liquid in said casing for venting air and gas therefrom when flow starts and for conducting siphon-breaking air from said casing to a portion of the system at the outlet side of the meter when the liquid lowers in said casing, and additional valved means for automatically admitting additional siphon-breaking air to said conducting means from a source other than said casing and unaffected by flow of liquid through the system.
2. In a liquid metering system in which unbroken siphonic action would empty the meter, said system including a liquid-conducting casing through which the liquid flows to said meter; valved conducting means controlled by the liquid in said casing for venting air and gas therefrom when flow starts and for conducting siphon-breaking air from said casing to a portion of the system at the outlet side of the meter when the liquid lowers in said casing, and additional valved means for automatically admitting additional siphon-breaking air to said conducting means from a source other than said casing and unaffected by flow of liquid through the system, the valve of said additional valved means being connected with and actuated by the valve of said valved conducting means.
3. In a liquid metering system in which unbroken siphonic action would empty the meter, said system including a liquid-conducting casing through which the liquid flows to said meter; the top of said liquid-conducting casing being provided with an air and gas vent, a valve for said vent, a valve-operating member connected with said valve and operated by the liquid in said liquid-conducting casing, a valve casing mounted on said liquid-conducting casing and communicating with said air and gas vent, a passage leading from said valve casing to a portion of the system at the outlet side of the meter for conducting siphon-breaking air thereto when said valve opens, said valve casing having another air inlet communicating with a source of air other than said liquid-conducting casing and unaffected by flow of liquid through the system for admitting additional siphon-breaking air, and a valve for said additional air inlet connected with the first named valve to be opened therewith and closed therewith.
4. In a metering system in which unbroken siphonic action would empty the meter; automatic means controlled by the system-contained liquid for conducting siphon-breaking air simultaneously from two independent sources to a portion of the system at the outlet side of the meter.
5. A structure as specified in claim 4; said automatic means including two valves for the two sources of air respectively, said valves being connected for operation in unison.
6. A structure as specified in claim 4; said automatic means including means for venting air from the portion of the system at the inlet side of the meter as said portion fills with the liquid.
7. In a liquid metering system in which unbroken siphonic action would empty the meter; automatic means controlled by the liquid in the system for venting air from a portion of said system at the inlet side of the meter as said portion fills with liquid and for later conducting siphon-breaking air from one source to a portion of the

system at the outlet side of the meter, and automatic means controlled by the liquid in the system for conducting additional siphon-breaking air from a second source to a portion of the system at the outlet side of the meter, the two automatic means being simultaneously operative.

8. In a liquid metering system in which unbroken siphonic action would empty the meter, said system having an air eliminator casing through which liquid flows to the meter; automatic means for venting air from said casing as the latter fills with liquid and for later conducting siphon-breaking air to a portion of the system at the outlet side of the meter, said automatic means including means for conducting some of said siphon-breaking air from said casing and the remainder of said siphon-breaking air from a second source independent of said casing.

9. In a liquid metering system in which unbroken siphonic action would empty the meter, said system having an air eliminator casing through which liquid flows to the meter; automatic means for venting air from said casing as the latter fills with liquid and for later conducting siphon-breaking air to a portion of the system at the outlet side of the meter, said automatic means including one valve for conducting some of said siphon-breaking air from said casing, and a second valve for conducting the remainder of said siphon-breaking air from a second source independent of said casing.

10. In a liquid metering system in which unbroken siphonic action would empty the meter, said system having an air eliminator casing through which liquid flows to the meter; automatic means for venting air from said casing as the latter fills with liquid and for later conducting siphon-breaking air to a portion of the system at the outlet side of the meter, said automatic means including one valve for conducting some of said siphon-breaking air from said casing, and a second valve for conducting the remainder of said siphon-breaking air from a second source independent of said casing, the two valves being connected for movement in unison.

11. In a liquid metering system in which unbroken siphonic action would empty the meter, said system including a liquid-conducting casing through which liquid flows to said meter, said casing being provided with an air and gas vent; a valve for said vent, an operating member for said valve actuated by the liquid in said casing, valve encasing means on the aforesaid casing to receive siphon-breaking air from said vent, said valve encasing means having an inlet to receive additional siphon-breaking air from an additional source, means for conducting the siphon-breaking air from said valve encasing means to a portion of the system at the outlet side of the meter, and a valve for controlling the passage of air from said additional source to said conducting means, this valve being connected with and actuated by the first named valve.

12. In a liquid metering system in which unbroken siphonic action would empty the meter, said system having an air eliminator casing through which liquid flows to the meter; a vent valve controlled by liquid in said casing for venting air and gases therefrom, and additional valve means actuated by said vent valve for conducting siphon-breaking air to a portion of the system at the outlet side of the meter.

13. In a liquid metering system in which unbroken siphonic action would empty the meter, said system having an air eliminator casing

through which liquid flows to the meter; a valve casing mounted on said air eliminator casing and having an air inlet independent thereof, an air conducting line extending from said valve casing to a portion of the system at the outlet side of the meter for conducting siphon-breaking air into

the same, a valve in said valve casing for controlling the passage of air from said air inlet through said air conducting line, a float in said air eliminator casing, and means operatively connecting said float with said valve. 5

WALTER S. BRUBAKER.
